(57) **CLAIM**

We claim the ornamental design for a chair, as shown and described.

DESCRIPTION

FIG. 1 is a front perspective view of a chair.

FIG. 2 is a front view of the chair shown in FIG. 1.

FIG. 3 is a rear view of the chair shown in FIG. 1.

FIG. 4 is a left side view of the chair shown in FIG. 1, the right side view being a mirror image thereof; and,

FIG. 5 is a top view of the chair shown in FIG. 1.

The broken lines having equal length segments represent

portions of the chair that form no part of the claimed design.

1 Claim, 5 Drawing Sheets
